CLAIM

The ornamental design for a beverage cap, as shown and described.

DESCRIPTION

FIG. 1 is a top perspective view of a beverage cap; FIG. 2 is a top view of the beverage cap of FIG. 1; FIG. 3 is a side view of the beverage cap of FIG. 1; FIG. 4 is a bottom perspective view of the beverage cap of FIG. 1; FIG. 5 is a top perspective view of the beverage cap of FIG. 1 coupled to an unclaimed bottle drawn in broken lines and with an unclaimed spout drawn in broken lines shown coupled to the beverage cap; and, FIG. 6 is a top perspective view of the beverage cap of FIG. 1 shown coupled to an unclaimed bottle drawn in broken lines. The broken lines in FIGS. 1-6 depict environment and form no part of the claimed design.
